(57) CLAIM

The ornamental design for a computer display, as shown and described.

DESCRIPTION

FIG. 1 is a top plan view of a computer display showing our new design;

FIG. 2 is a front elevational view thereof;

FIG. 3 is a bottom plan view thereof;

FIG. 4 is a rear elevational view thereof;

FIG. 5 is a left side elevational thereof;

FIG. 6 is a right side elevational view thereof;

FIG. 7 is a cross-sectional view taken along the line 7—7 as shown in FIG. 2 thereof, which omits the internal structure;

FIG. 8 is a front elevational view with the stand extended vertically;

FIG. 9 is a right side elevational view with the stand extended vertically;

FIG. 10 is a cross-sectional view taken along the line 10—10 as shown in FIG. 8 with the stand extended vertically, which omits the internal structure;

FIG. 11 is a perspective view of the top, front and right side thereof; and,

FIG. 12 is a perspective view of the rear, top and left side thereof with the cable cover attached.
